(57) **CLAIM**

The ornamental design for a pet carrier, as shown and described.

DESCRIPTION

FIG. 1 is a perspective view of the pet carrier; FIG. 2 is left side elevational view thereof; FIG. 3 is a front elevational view thereof; FIG. 4 is a right side elevational view thereof; FIG. 5 is a rear elevational view thereof; FIG. 6 is a top plan view thereof; and, FIG. 7 is a bottom plan view thereof.

The broken lines are intended to illustrate non-claimed subject matter, are for illustration only and form no part of the claimed design.

In particular, the broken lines at the top and bottom of the claimed design are unclaimed and represent the bounds of the claimed subject matter, and the broken lines that extend along the mesh-like portions of the claimed design are unclaimed stitching.
